FREQUENCY DETERMINING UNIT

Samuel Alexander Bokovoy, Verona, N. J., assignor to Federal Telephone and Radio Corporation, New York, N. Y., a corporation of Delaware

Application July 20, 1944, Serial No. 545,847

7 Claims. (Cl. 171—327)

This invention relates in general to oscillator or resonator units for crystal controlled oscillator circuits and consists of an improved design and structural arrangement adapted for the production of a materially simplified and economical unit offering important advantages over constructions as heretofore employed. The features thereof are particularly valuable as incorporated in the smaller types of unit assemblies of the so called bottom loading type employing a protective cover formed with an internal socket or recess for the reception of the crystal and associated electrodes and spring and a base member for assembly therewith carrying opposite contacts to engage an electrode at one side and at the opposite side with the spring associated with the opposite electrode and with the base provided with the usual terminal pins.

In oscillator units of the type to which this invention particularly applies, difficulties have heretofore been encountered in the assembling of the crystal and associated parts including the opposite electrode plates and in returning them in their proper co-relation. While in certain forms of structure the objectionable difficulties of properly assembling have been partially overcome by the employment of a separable frame member or chase in which the crystal and electrodes are initially assembled there is still present in such structures difficulties particularly in the withdrawal of the separable elements of the assembly in addition to the objectional requirement of additional parts.

In accordance with the present invention the elimination of the requirement for the separable frame member and the objections of its use is accomplished with a desirable improved compactness for reduction in size and moreover in a manner to insure of an improved removable relation and retaining of the parts. In addition there is produced a related structural arrangement wherein upon withdrawing or separation of the base from the cover there is simultaneously effected a partial withdrawal of the contained parts including the crystal electrodes and compression spring so as to effect their partial removal into a projected position thereby to facilitate grasping by the fingers to expedite removal. This is an important advantage in the disclosed type of assembly wherein the crystal is supported for thickness oscillation and shear mode of vibration and is engaged by the electrodes from each side with a compressive force. As in the final assembly the separable parts are desirably fully received within the socket of the cover, including a spring ef-

fective to impart the mounting pressure on the electrodes and crystal, an added difficulty is presented to the withdrawal of the parts. This difficulty is enhanced in the desirable small unit structures.

The described and other features and advantages of the present invention will be more fully understood by reference to the accompanying drawing wherein like reference characters are applied to the corresponding parts in the several views.

In the drawing:

Fig. 1 is a view in vertical, longitudinal section showing an approved embodiment of the features of the invention in a resonator unit structure adapted for the protective mounting of a piezoelectric crystal element in the customary manner for thickness oscillation.

Fig. 2 is a top plan view of the base member of Fig. 1 showing the contact members assembled therewith.

Fig. 3 is a central vertical cross sectional view taken on line 3—3 of Fig. 1 of the assembled oscillator unit structure.

Fig. 4 is a view generally similar to Fig. 3 but with the base and cover plates partially separated to illustrate the simultaneous partial withdrawal of the separable crystal and electrode elements.

Referring now in detail to the disclosed and preferred embodiment of the invention, 1 indicates a base portion or member of molded insulating material. This base portion, shown of rectangular form, has rigidly secured thereto longitudinally spaced and aligned mounting pins 2 which extend vertically through the insulating body of the base. In the customary manner they are rigidly secured by being molded in the material of the base portion. To the upper or inwardly directed surface of the base member there are secured vertically extended resilient contact elements or plates 3 in laterally spaced relation. The contact plates are provided with securing flange portions 4 affixed to the upper ends of the mounting pins 2 as by welding for electrical connection therewith. In cooperating relation with the base there is provided a cover member 5 of molded insulating material formed with an internal and downwardly open rectangular socket 6 adapted, in conjunction with the base portion, to provide a hermetically sealed protective enclosure for the crystal and associated mounting parts. To the latter end, provision is made for securing the cover and base members consisting of the securing screws 7 threaded into cover apertures 8 and passed through base apertures 9 to

permit of securely fastening of the cover and base members with the interposed elastic sealing washer 10. The cover socket is of elongated rectangular formation having parallel vertical side and end walls and having its inner wall surface formed with spacing shoulders or bosses 11. It is further formed with its vertical side walls provided with vertically extending, centrally aligned, guideway grooves 12. These are formed to extend inwardly from the open end of the socket to a position midway of its depth and with the inner ends of the grooves tapered at 13 so that the opposed side walls of the respective grooves are at their innermost portions upwardly and inwardly inclined.

The crystal element is shown at 14 of the customarily employed rectangular plate form and in the assembly is received within the socket and positioned between the opposite electrodes 15 likewise of rectangular plate formation and of a character to make proper electrical and cooperating contact with the face of the crystal in a manner to avoid damping of the vibrations. The outer face of one of the electrodes, the left hand electrode as here shown, is engaged by the inner face of one of the resilient base contact plates 3 while the opposite or right hand electrode is engaged by the inner enlarged turn 16 of compression coil spring 17 which is positioned to effect a pressure clamping or supporting of the crystal element. The vertical dimensions of the crystal and associated electrodes and washer are such as to be rather closely confined between the bosses 11 of the cover and the upper surface of the base portion thereby to insure of accurate positioning and retention of these elements in cooperating relation. The upper surface of the base portion is formed with an inward recess or groove 18 which in its dimensional relationship to the supporting flanges of the resilient contacts insures the proper alignment of the contact plates through assembling of the contact plates with the block and terminal pins 2. Also as best shown in Fig. 2, in the forming of the groove 18 spaced bosses 19 are provided in substantially vertical alignment with the bosses 11 to cooperate therewith in the positioning of the insert members.

The improved facility of, and other advantages incident to, the loading and unloading of the insert elements or assembling of the device will be best understood by reference to the Figs. 3 and 4. In the loading of the unit the crystal element with the electrode plates positioned at each side thereof, are dropped into position or inserted within the cover. The coil spring, desirably of the conical form as shown, is then inserted to hold the electrodes and crystal together. The resilient contact plates 3, assembled with the base, are then engaged or inserted within the grooves 12 of the cover member 5 and as they are advanced inwardly will engage the outer surfaces of the left hand electrode and the spring 17. As a result of the camming action of the tapered portions 13 of the groove, contact plates 3 will be inwardly deflected to establish a final assembly and resilient clamping of the crystal as the base and cover are moved into homed or closed position as shown in Fig. 3. As will be apparent, the arrangement provides insurance that the resilient contact is properly received behind the spring 17, as it enters, thereby to avoid an end on engagement with the spring as might cause displacement of the spring from its intended position.

In the unloading of the insert parts of the device on its disassembly further advantage and facility are obtained. This will be appreciated by reference to Fig. 4 from which it will be noted that as the base element is withdrawn from its assembled position, during the initial period of its movement, the insert elements will be retained in pressure engagement with the opposite contact plates 3 in a manner whereby they will be likewise partially withdrawn from the socket into an accessible exposed position. They are released from such withdrawing pressure only after the ends of the contacts 3 are fully received within the entry or guideway grooves 12. They are accordingly more readily removed for inspection or replacement.

Additional advantages presented by the improved structure as described include facility in accommodating different sizes of crystals by varying the dimensions of the socket, a material reduction in the parts with resulting economy in required tooling and stocking of parts together with reduction in tolerances required. The contact plates and also the pin terminals 2 may desirably be made of nickel silver so as to permit of their being soldered or welded without flux resulting in further advantage of avoiding loose flux and acid influence. Other modifications may be made therein without departing from the scope of the invention as defined in the claims. As illustrative, in place of the securing screws for attaching the base to the cover as shown it is proposed that a polystyrene cement may be employed between the engaging surfaces of the base and cover thus to provide for hermetically sealing with the elimination of the screws.

What is claimed is:

1. A frequency determining unit of the character described comprising a container formed to provide a socket for the reception of a resonator element, a crystal element and opposite electrodes associated therewith adapted to be received within the container, said container being composed of a cover member and a separable base for assembly therewith, contact elements carried by the base and said cover being provided with guide means formed to effect deflection of the contacts into a contacting position upon assembling of the parts.

2. A frequency determining unit of the character described comprising a container formed to provide a socket for the reception of a resonator element, a crystal resonator and opposite electrodes associated therewith adapted to be received within the sockets, said container being composed of cover and base members, contacts carried by one of said members and the other of said members being formed with guideway grooves in registration with the contacts and formed to effect a deflection of the contacts into a circuit completing contact position upon full assembling of the members.

3. A frequency determining unit of the character described comprising a container formed to provide a socket for the reception of a resonator element, a crystal resonator element having opposite electrodes associated therewith received within the socket, a resilient element positioned to impart a holding pressure on the electrodes and crystal element, said container being composed of a cover member having a bottom opening socket and a base member fitted to close the socket, said base being provided with terminal pins for plug in connection and with projecting resilient contacts connected with the pins, the socket being formed with guideway grooves in

its side walls positioned for registration with the base contacts and formed with deflecting surfaces positioned to be engaged by the contacts prior to full assembly.

4. A frequency determining unit of the character described comprising an insulating container formed to provide a socket for the reception of a resonator element, a crystal resonator element having opposite electrodes associated therewith positioned within the socket, a coil spring positioned to impart a holding pressure on the electrodes and crystal element, said container being composed of a cover member having a bottom opening socket and a base member fitted to close the socket, said base being provided with projecting resilient contacts and the cover socket being formed with guideway grooves in its side walls positioned for registration with the base contacts and formed at their inner ends with deflecting surfaces positioned to be engaged by the contacts prior to full assembly position and said deflecting surfaces being positioned to at least partially underlie the spring.

5. A frequency determining unit of the character described comprising an insulating container for the reception of a resonator element, said container being composed of a cover member having a bottom opening socket and a base member fitted to close the socket, said base being provided with terminal pins for plug in connection and with projecting resilient contacts connected with the pins, said contacts having bases positioned within a socket in the base member formed to determine the position of the contacts, said cover socket being formed with guideway grooves in its side walls positioned for registration with the base contacts and having inward deflecting surfaces to be engaged by the contacts in an intermediate assembly position, a crystal resonator element and oppositely inserted electrodes positioned within the cover socket and a resilient element positioned to impart a holding pressure on the electrodes and crystal element and to be engaged by one of the contacts

for clamping of the insert elements between it and the opposite contact.

6. A frequency determining unit of the character described comprising an insulating container for the reception of a resonator element, said container being composed of a cover member having a bottom opening socket and a base member fitted to close the socket, said base being provided with terminal pins for plug in connection and with projecting resilient contacts connected with the pins, said cover socket being formed with guideway grooves in its side walls positioned for registration with the base contacts and having inward deflecting surfaces to be engaged by the contacts prior to full assembly, a crystal resonator element, oppositely positioned electrodes and a resilient element adapted to be inserted within said socket, one of said electrodes and said resilient element being engaged by the contacts when inwardly deflected for clamping the insert elements.

7. A frequency determining unit of the character described comprising an insulating container for the reception of a resonator element, said container being composed of a cover member having a bottom opening socket and a base member fitted to close the socket, said base being provided with terminal pins for plug in connection and with projecting resilient contacts connected with the pins, said contacts being mounted within a socket in the base member formed to determine the position of the contacts, said cover socket being formed with guideway grooves in its side walls positioned for registration with the base contacts and having inward deflecting surfaces to be engaged by the contacts prior to full assembly, a crystal resonator element, oppositely positioned electrodes and a resilient element adapted to be inserted within said socket, one of said electrodes and said resilient element being engaged by the contacts when inwardly deflected for clamping the insert elements.
